COMBINED BUTTERFLY METAL SCULPTURE AND STAND

Kenneth M. Scott, 2450 W. 18th St.,
Eugene, Oreg. 97402

Filed June 22, 1973, Ser. No. 372,476

Term of patent 14 years

Int. Cl. D11—02

U.S. Cl. D29—23 B

FIG. 1 is a left side elevational view of a combined butterfly metal sculpture and stand showing my new design;

FIG. 2 is a top plan view; and

FIG. 3 is a front elevational view.

I claim:

The ornamental design for a combined butterfly metal sculpture and stand, as shown.
